[57] CLAIM

The ornamental design for a chair or similar article, as shown and described.

DESCRIPTION

FIG. 1 is a front and left side perspective view of a chair showing my new design;

FIG. 2 is a rear elevational view thereof;

FIG. 3 is a front elevational view thereof;

FIG. 4 is a top plan view thereof; and

FIG. 5 is a right side elevational view thereof.

The chair is characterized in part by runs of rope woven in a figure eight pattern and transversely spaced at each end by a wrap of rope around a support.

FIG. 1

FIG. 2

FIG. 3

FIG. 4

FIG. 5
